UNITED STATES PATENT OFFICE.

OTTO A. BANNER, OF MILWAUKEE, WISCONSIN, ASSIGNOR TO THE FALK CORPORATION, OF MILWAUKEE, WISCONSIN, A CORPORATION OF WISCONSIN.

OIL ENGINE.

Application filed March 17, 1922. Serial No. 544,412.

This invention relates to oil engines, and more particularly, to that type of oil engine in which a restricted passage or throat is employed between the compression chamber 5 and the working portion of the cylinder.

One object of the present invention is to improve the combustion in engines of this type.

Another object is the provision of an engine of this type which will operate successfully at high as well as low compression pressures.

Other objects and advantages will hereinafter appear.

One embodiment of this invention is illustrated in the accompanying drawings, in which:

Figure 1 is a sectional view of an oil engine constructed in accordance with the present invention.

Figure 2 is a fragmentary plan view of a portion of the combustion chamber and one of the injection nozzles associated therewith.

Figure 3 is a detail of one of the fuel injection nozzles shown in Figures 1 and 2.

The engine selected for illustration is an upright, four-cycle engine of the solid injection or pump spray type, although the invention is equally applicable to horizontal engines and to engines operating on the two stroke cycle. This engine includes one or more cylinders 10 provided with the usual water jackets 11. The cylinder head 12 is of a well known construction having the usual exhaust and air inlet valves 13 and 14 and provided with water jackets 15. The compression chamber is formed by a water cooled member 15 interposed between the cylinder head 12 and cylinder 10. In order to gain access to the compression chamber this member is preferably formed as a separate piece to permit ready removal of the cylinder head therefrom.

The compression chamber is of elongated form extending transversely of the cylinder and having downwardly and inwardly inclined walls 16 leading to a restricted throat or passage 18, preferably centrally disposed, through which communication is effected with the working portion of the cylinder.

The piston 19 shown is of usual construction and of a stroke preferably such as to force practically all the air from the cylinder proper into the compression chamber during the compression stroke, although the stroke may be such that at compression dead center a body of air is retained within the cylinder proper.

The fuel is introduced preferably through a pair of injection nozzles 20 of a type such as described in the copending application of Otto A. Banner and Jacob Schlumberger, filed March 17, 1922, Serial No. 544,427.

These nozzles are arranged in the opposite ends of the compression chamber and each is designed to produce a pair of convergent fuel jets which meet at a point adjacent the end of the nozzle. Each nozzle is provided with an end cap 26 having a pair of fuel discharge ducts 27. These ducts communicate with a chamber formed by a depression 28 within the cap and communicating with a fuel passage 29, which is supplied with liquid under pressure through a pipe 25. These ducts are so related as to produce the convergent fuel jets heretofore mentioned. The fuel is injected under pump pressure of such intensity as to completely atomize the fuel as it issues from the nozzle.

The impact of the two jets produces a substantially flat fuel spray in each end of the chamber, as indicated in Figure 2, each spray comprising a substantially flat relatively dense core of fuel particles surrounded by a layer of lighter fuel mist, this lighter fuel mist being formed by the frictional contact of the spray with the air as the spray penetrates the body of air in the chamber. The nozzles are so disposed as to direct the two sprays toward and against each other the impact of the sprays producing a narrow elongated fuel cloud extending transversely of the chamber adjacent the restricted throat 18. The cloud thus formed comprises a dense core of fuel particles surrounded by a layer of lighter fuel mist.

In my copending application, Serial No. 544,413, filed March 17, 1922, I have disclosed an engine embodying an elongated

chamber of similar form in which the fuel is introduced in the form of opposed flat sprays similar to those in the engine herein described. In the engine of that application the injection nozzles are co-axially arranged, so that the two sprays lie in substantially the same plane and the fuel cloud formed by the impact of the sprays is not thrown toward the throat. With that arrangement extreme accuracy in the setting of the nozzles is required to insure good impact, since any inaccuracy resulting in an offset relation of these sprays permits the sprays to pass each other without impacting. In the engine herein described the nozzles are so disposed as to give the sprays a slight inclination, so that good impact is assured without requiring the accurate setting of the nozzles above noted. And by making this inclination sufficiently slight there is practically no tendency to throw the fuel cloud toward the throat.

The fuel is introduced in a ram-like charge immediately before compression dead center, at a time when the movement of the piston 19 has practically ceased and there is practically no flow of air through the throat 18. The light fuel mist originally surrounding the sprays and surrounding the denser cloud formed by the impact, vaporizes readily and starts burning almost simultaneously with the injection. This initial combustion effects the vaporization of the coarser fuel particles contained in the concentrated fuel cloud and prepares the same for quick burning. Actual combustion of the fuel in the concentrated cloud can take place only as it is brought into contact with the oxygen of the air necessary to carry out the chemical reaction.

This mixture and contact of the air and fuel within the cloud is effected, during the early part of the working stroke, by the turbulence set up in the chamber, throat and piston space at that time. This turbulence is started by the initial combustion of the fine fuel mist and is continued and increases as the piston starts its working stroke and permits the contents of the chamber to pass through the throat into the piston space. Thus, although initial combustion occurs in the chamber and almost simultaneously with the injection of the fuel, yet the major portion of the combustion occurs within the throat and piston space, as the fuel in the concentrated cloud is mixed with the oxygen of the air flowing from the chamber to the piston space.

It has been found that an engine constructed and operated in the manner above described gives excellent results when comparatively high compression pressures are employed, although it is not necessary to operate at compression pressures as high as those required in the Diesel engine. It has also been found that, although the combus-

tion is prompt and complete, it does not occur as a violent explosion at compression dead center. This may be due to the fact that the fuel is not introduced until immediately before compression dead center and some interval of time is required, after the initial fuel injection, before a good combustible mixture develops. By injecting the fuel at this time all danger of pre-ignition is, of course, avoided.

Various changes may be made in the embodiment of the invention hereinabove described, without departing from or sacrificing any of the advantages of the invention as defined in the appended claims.

I claim:

1. In an internal combustion engine the combination of a cylinder having an elongated chamber extending transversely thereof, the transverse sectional areas of said chamber being substantially rectangular and increasing in size from the ends toward the center, a passage between the center of said chamber and the working portion of said cylinder, and injection nozzles at the opposite ends of said chamber for directing opposed substantially flat fuel sprays from the ends toward the center of said chamber.

2. In an internal combustion engine the combination of a cylinder having an elongated chamber extending transversely thereof, the transverse sectional areas of said chamber being substantially rectangular and increasing in size from the ends toward the center of said chamber, a passage between the center of said chamber and the working portion of said cylinder, and means for producing a plurality of impacting fuel jets in each end of said chamber to form a substantially flat fuel spray directed toward the center of the chamber.

3. An internal combustion engine having a cylinder provided with an elongated chamber extending transversely thereof, inlet and exhaust valves in one wall of said chamber, a restricted passage between said chamber and the working portion of said cylinder, and means including airless fuel injection nozzles at the opposite ends of said chamber for producing opposed downwardly inclined substantially flat fuel sprays in said chamber immediately prior to compression dead center.

4. An internal combustion engine having a cylinder provided with an elongated chamber, a restricted passage between said chamber and the working portion of said cylinder, inclined relatively flat walls in said chamber leading toward said passage, and means for directing opposed substantially flat inclined fuel sprays from the opposite ends of said chamber toward said passage.

5. In an oil engine the combination of a cylinder having a relatively shallow elongated chamber extending transversely there-

of, said chamber having a substantially flat top wall and substantially flat bottom walls inclined away from said top wall toward the center of said chamber, means for cooling the walls of said chamber, a restricted passage between said cylinder and chamber, and airless fuel injection nozzles at the opposite ends of said chamber for producing opposed substantially flat inclined fuel sprays therein which meet adjacent said passage. 10

In witness whereof, I hereunto subscribe my name this 2nd day of March, 1922.

OTTO A. BANNER.
